UNITED STATES PATENT OFFICE.

AXEL A. SAWMAN, OF BROOKLYN, NEW YORK.

BALANCED DAVIT.

1,094,750.

Specification of Letters Patent. Patented Apr. 28, 1914.

Application filed December 5, 1913. Serial No. 804,837.

To all whom it may concern:

Be it known that I, AXEL A. SAWMAN, a citizen of the United States, and a resident of the borough of Brooklyn, in the county of 5 Kings and State of New York, have invented certain new and useful Improvements in Balanced Davits, of which the following is a specification.

This invention relates to improvements in 10 balanced davits for raising and lowering ships' boats.

It is an especial purpose of the invention to provide davits and the operating mechanism thereof, so constructed and arranged 15 that the various forces and strains acting upon the davits shall be so proportioned and related to each other that the davit shall be in "balance" and remain securely in whatever position it may be until the attendants 20 operate the mechanisms for shifting the davit to another position.

Other advantages of the invention are that it provides a simple, cheap and strong construction with very few parts, which parts 25 are easy of access and assembling. In fact a davit installation consists of only two principal parts, *i. e.* the davit *per se* and its frame.

Another advantage is that practically all 30 the mechanism for raising and lowering the davit is mounted on the davit itself.

A further advantage is that the crank or handle by which the davit operating mechanism is actuated is located in such a position, 35 at the side and well forward of the davit, that the operator can watch the boat as he raises or lowers the boat; whereas with davits, as heretofore constructed, the operator is in such a position that he cannot 40 not watch the boat, and therefore is at a great disadvantage in controlling the movements of the davit, as compared with a man who can watch the boat.

Other advantages will be evident from the 45 description hereinafter set forth, in connection with the accompanying drawings, whereof—

Figure 1 is a broken side elevation of a davit and its operating mechanism, the davit 50 being in its elevated position; Fig. 2 is a side elevation of the same parts, but showing the davit in its lowest position; Fig. 3 is a broken front elevation and section of the davit and operating mechanism, and indicating one end of a boat suspended by tackle from the head of the davit; Fig. 4 is a horizontal section on the broken line 4—4 of Fig. 1; Fig. 5 is a broken section and elevation of the bevel gear and worm screw on the line 5—5 of Fig. 2.

It being understood that two davits are arranged in pairs, one davit for each end of a boat, and that the construction of the davits and their operating mechanisms are similar to each other, each davit A, being 60 suitably equipped with tackle and falls, is provided at a suitable point, relatively nearer its lower end, with trunnions *a* turning on an axle *b* in bearings *c*, secured to frame B. I prefer to form said trunnions *a*—*a* hollow, so as to turn on the said transverse axle *b* which is carried by said bearings *c*. Said davit A, of any suitable material, may either be straight as indicated in Fig. 2, or curved as indicated in Fig. 3, and 65 is preferably larger and heavier at its lower part than at its upper, to aid in securing the aforesaid balance. Said frames B preferably consist of two upright rectangular forgings suitably fastened to the deck of the 70 ship, and spaced apart sufficiently to permit the lower end of said davit to work between them, and I prefer to form the foot block E of said davit A of such width as 75 to fit with easy working fit between said 80 frames B.

A worm screw F is mounted on said davit A parallel thereto, the lower end of said worm screw turning in a socket in the said block E, and the upper end thereof turning 85 in a socket in the bracket *d*, which is firmly secured to said davit A. Said worm screw F is provided with a bevel gear G meshing with a bevel gear H fixed on a stud or axle, revolving in a bracket I carried by said 90 davit A, and being provided with a crank J for revolving said gear H. I prefer the construction shown in Fig. 5, wherein said bevel gear G fits on the square enlarged 95 portion of the end pivot *g* of said worm screw F, and the axial stud *h* of said bevel gear G turns in a hole in said bracket *d*, being retained in position by a nut *i*, and washer as indicated in Fig. 5. Said worm screw F works through a nut K, which is 100 pivoted between the upper ends of rocking arm L—L, which are in turn pivoted at their lower ends as at *l*—*l*, to flanges *l'*—*l'* of said frames B—B, (Fig. 3); said arms L—L being preferably bent inwardly and upwardly about as indicated in Fig. 3. By 105 this construction, said nut K can both os-

cillate on its own pivot and also swing about the pivots of said arms L—L, so as to accommodate itself to any angle and position between the extreme limits of the motion of 5 said davit A. The position of said pivots L—L is such, that when said davit A is at its extreme upper or inboard position, that the line through the pivots of said nut K and said arms L—L inclines upwardly and in 10 wardly from the longitudinal axis of said worm screw F. Such angular relation of the said lines may be more concisely expressed by the phrase, the arms L—L are inclined inwardly from said davit A. When the said 15 davits and the worm screw, the nut and the rotating arms are arranged as hereinbefore described, then the davit will be "balanced" in whatever position it assumes, and will remain securely in that position until said 20 worm screw is revolved to shift the davit to another position. I prefer to provide the lower part A' of said davit with a longitudinal dove tail rib e, on which fits a dove tail groove in the edge of said nut K. 25 It will be evident from the foregoing description that the invention operates in the following manner, one or more men being stationed at each davit to revolve said crank J, and handle the tackles. If a boat 30 is to be lowered, then the chocks (not shown) having been removed, the men at the two davits turn the said cranks J and thereby ultimately revolve said worm screw F by means of the worm gears G, H, in the direction for moving said nut K downwardly. 35 Such motion of said nut K swings the lower ends of said davits inboard, and the outer end thereof outboard, by reason of the aforesaid angular position of said arms L—L. 40 with respect to said davits A, until said davits A attain their extreme outboard position, when the boat will be lowered by the

men at the tackles. To raise the boat, the revolution of the worm screws will be in the opposite direction from that for lowering it, and the davits will as hereinbefore stated, be in balance through all their movement, so that they will remain securely with the boat hanging from them, in any position. A stop may be provided to properly 50 limit the outboard motion of the davits.

Now having described my improvements, I claim as my invention.

1. The combination with a swinging davit of a worm screw carried thereby, and of 55 means to revolve said screw, a nut engaging said screw, and pivoted arms carrying said nut and arranged at an angle with said davit, whereby said davit is in balance in all its 60 positions.

2. The combination with a swinging davit of a worm screw carried thereby, rotary gears operatively connected therewith and means to rotate said gears, a nut engaging 65 said worm, and oscillating arms carrying said nut and arranged at an angle with said davit for the purpose hereinbefore described.

3. The combination in a davit installation of a swinging davit, a frame on which said davit is pivoted, a worm screw mounted on 70 said davit, bevel gears for revolving said screw and means to operate said gears, and an oscillating arm on which a nut engaging said worm is pivoted, said oscillating arm being at an inwardly and upwardly angle 75 from said davit.

Signed at Brooklyn, in the county of Kings, and State of New York, this 4th day of December, A. D. 1913.

AXEL A. SAWMAN.
